CLAIM

The ornamental design for a strut for a construction set, as shown.

DESCRIPTION

FIG. 1 is a perspective view of a strut for construction set showing my new design;

FIG. 2 is a side elevational view thereof;

FIG. 3 is a bottom plan view thereof;

FIG. 4 is an end elevational view thereof; and,

FIG. 5 is an end elevational view of the end opposite that shown in FIG. 4.
